AUTOMATIC SWAGING METHOD AND TOOL
Charles T. Schellhammer, Thompsonville, Conn., assignor
to United Aircraft Corporation, East Hartford, Conn.,
a corporation of Delaware

Filed June 8, 1966, Ser. No. 556,016
1 Claim. (Cl. 72—435)

ABSTRACT OF THE DISCLOSURE

A total and die arrangement for installing electrical connectors in a perforated circuit board wherein a bottom die centers and supports the hollow connector in the circuit board and a triggering swaging tool easily upsets the connector end portion above the board and fixes it to the board.

This invention relates to methods of swaging electrical 20 connectors and the like and special tools therefor.

In the past metal electrical connectors were placed in spaced holes in perforated insulated boards with the connectors protruding from the board and electrical or electronic units are then soldered to these connectors. The method used for fixing the connectors to the board was time consuming and awkward. The connectors are hollow metal units and are inserted into one of the holes. A die is positioned against one end of the connector and the board with the connector inserted had to be held against the die. A second swaging die would then have to be held against the other end of the connector and a hammer was used to strike a blow against the second die. This awkward manipulation quite frequently resulted in splitting the hollow connectors or damaging the board.

It is therefore an object of this invention to utilize an automatic swaging tool which needs only one separate die and thereby eliminating one tool, as well as facilitating the speedy installation of connectors.

These and other objects of this invention will become readily apparent from the following detailed description of the methods of operation and the structure shown in the drawing in which

FIG. 1 is a partial sectional view of the tools and parts just prior to operation.

FIG. 2 is a partial sectional enlargement of the tools and parts in contact just prior to the swaging operation and

FIG. 3 is an enlarged partial sectional view after the swaging operation.

Referring to FIG. 1, an automatic swaging tool 10 is shown just above the assembled working pieces. The tool is a well known type having an outer hand held portion 12 and a spring loaded plunger 14. This type of tool is well known in the art and is normally constructed as a centering punch and may be of the type shown in Patent No. 3,029,512 issued April 17, 1962 to J. N. Saxton. Motion of the outer case 12 in a direction of the arrow and with respect to the portion 14 after the latter engages a work piece, loads a spring which eventually releases the member 14 to impart a sudden hammering blow.

I have adopted the centering punch with a swaging

10

2

tool 16 which will be described in better detail hereinafter.

As seen in FIG. 1 a perforated insulated board 20 is shown having a hollow electrical connector 22 inserted in one of the holes and engaged by a lower die 24.

As better seen in FIG. 2 the swaging tool 16 is placed into engagement with the hollow electrical connector 22. The connector 22 includes a flange 30 which positions it in the hole so that it extends a predetermined distance on either side thereof. The lower die 24 engages the flange 30 by means of an annular recess 32 and also by means of a vertical riser 34 engaging a slot 36 in the connector.

15 The swaging tool 16 includes a centering guide 40 including a flared shoulder 42 protruding into the hollow connector 22.

It can be seen that in this position of the tools the operator can merely hold the board 20 in position against the die 24 while the swaging tool assembly can be operated to impart a blow to the upper portion of the connector 22.

As seen in FIG. 3 this operation will result in a very uniform swaging or flaring of the upper end of the connector 22 as seen at 46.

25 It will be apparent that as a result of this invention not only has one tool been eliminated in a swaging method but besides the need for awkward manipulation by the operators has been eliminated. Furthermore, speed of operation has been enhanced.

30 I claim:

1. A swaging die set for use with a spring loaded hammering device having a triggered member adapted to strike that portion of a connector extending above an electrical connector board, said connector extending through said board and also projecting below the board, a die adapted to be positioned adjacent the bottom of said board in alignment with a hole therein and having an aperture receiving said connector, said die including an annular recess, a vertical riser located centrally of the recess, said connector including a flange engaged by said annular recess, a slotted portion of said connector extending into said aperture and receiving said vertical riser to firmly position said connector, and a swaging tip carried by said triggered member for engaging the hollow connector, said tip including a centering guide extending into the hollow connector and a flared shoulder extending laterally from said centering guide, said flared shoulder swaging said connector end upon triggering impact of said triggered member.
